UNITED STATES PATENT OFFICE

HUGO H. WERMINE, OF VILLA PARK, ILLINOIS, ASSIGNOR TO BELDEN MANUFACTURING COMPANY, OF CHICAGO, ILLINOIS, A CORPORATION OF ILLINOIS

ELECTRIC CONNECTER

Application filed March 5, 1928. Serial No. 259,297.

This invention relates to electric connectors, and more particularly to the female part of a separable plug connector which is particularly adapted for use in connection with 5 a floor cord or extension wire.

One object of the invention is to provide a small, compact, neat appearing plug connector of the above mentioned type which can be manufactured very cheaply and economi- 10 cally.

Another object is to provide in a plug connector, means for facilitating connection of the connector to the conductor or conductors of the floor cord or extension wire, and which 15 means is capable of being manipulated by a person unskilled in the art of electric connections.

Still another object is to provide means for anchoring the connector on the end of the 20 floor cord so as to relieve the conductor elements of the cord from such strain as might be imposed thereon by any tendency to separate the connector from the cord.

It is also an object of this invention to pro- 25 vide a connector of the class described, which is light in weight, yet strong and durable, and in general, to provide an improved connector of the type described. Other objects and advantages of the invention will be understood 30 by reference to the following specification and accompanying drawing wherein I have illustrated a connector embodying a selected form of my invention, and in which drawing:

Fig. 1 is an assembly view showing one use 35 to which my improved connector may be applied.

Fig. 2 is a section on the line 2—2 of Fig. 1.

Fig. 3 is a bottom plan of my improved connector, a cover plate being removed so as to 40 show the interior of the connector.

Figs. 4 and 5 are sections on the lines 4—4 and 5—5 respectively of Fig. 3, and

Fig. 6 is a perspective of one of the contact elements constituting a part of my improved connector.

Referring now to the drawings, I have shown in Fig. 1 a floor cord including preferably, a flat relatively wide but thin rubber covered duplex conductor 10 connected to a 50 duplex extension cord 11 by means of a con-

nector 12 of suitable construction, the free ends of the conductor 10 and extension 11 being provided with connectors 13 and 14 respectively. The connector 14 on the free end of the extension 11 may be of any suitable 55 type of male connector plug, and the connector 13 is preferably a female connector plug constructed in accordance with the present invention.

A conductor cord assembly such as above 60 described is particularly adapted for use in a room where a convenient electric outlet is located on one wall of the room and it is de- 65 sired to operate an electrical device in a re- 70 mote part of the room where no electric out- 75 let is conveniently available. The flat du- 80 plex conductor 10 is adapted to lie flat on the floor and to be substantially concealed by a rug or other floor covering, the connectors 12 and 13 being positioned adjacent edge por- 85 tions of the covering so that a minimum of the end portions of the flat conductor 10 will be visible.

The connector 14 on the free end of the ex- 75 tension wire 11 may be connected to the avail- 80 able outlet and the connector 13 then serves as an outlet adjacent the location of the device it 85 is desired to operate. The extension wire 11 is preferably provided with an ornamental covering so that it does not detract materially 90 from the appearance of the room.

The connector 13 is preferably formed of suitable insulating material which may be molded into the desired shape and which, when set or hardened, will be strong and dur- 95 able, and will present a neat and pleasing ap- 100pearance. In the present instance I prefer to make the main body member 15 of the connector of a phenol condensation product. This material has all the desirable features 90 mentioned above and is such that it may easily be molded to the desired shape, and when hardened presents a polished finish which enhances the appearance of the article. The body member 15 is provided with a pair of 95 apertures 16 and 17 extending from top to bottom thereof, and a recessed bottom portion 18 which is formed by providing an annular flange 19 depending from the bottom 18.

Nuts such as shown at 20 in Fig. 5 are 100

molded in place in the bottom portion of the body member, the outer surface of the nuts being knurled or otherwise roughened to afford a good grip for the body material on the nut members. Contact members 21 such as shown in Fig. 6, which include a leg portion 22 and flange portion 23, are provided and secured, one to each of the nut members 20 as shown in Fig. 5. The flange portion 23 of the contact member is apertured as indicated at 24, to fit over an end portion of the nut which projects beyond the bottom surface 18 of the body member, and said projecting end portion of the nut member is swaged over the flange portion 23 around the aperture 24. The aperture 24 is preferably tapered so that the end portion of the nut may be swaged to lock the contact member against the bottom surface 18 of the body without projecting beyond the bottom face of the flange portion 23.

As best shown in Figs. 4 and 5, the leg portions 22 of the respective contact members are disposed in the apertures 16 and 17 respectively, and are bowed outwardly slightly so that when the prongs 25-25 of a connector plug such as 44 (Fig. 2) are inserted into the apertures 16 and 17, good electrical contact will be established between the leg portions 22-22 and the said prongs 25-25. The leg portion 22 of each of the contacts is also preferably provided with an offset portion or hump 26 which is adapted to interlock with an aperture such as is usually provided in the prongs 25 of the male connector plug.

The apertures 16 and 17 are preferably undercut as indicated at 26' and 27 so that the upper ends of the contact members will be covered and will be thereby protected from engagement by the ends of the prongs of the connector plug which are inserted into the apertures. This arrangement avoids the possibility of injuring the contact members by engagement between the ends of the prongs of the male connector part and the ends of the contact members in the female connector part.

For facilitating connection to the connector, of the wires of a duplex conductor cord such as the above described relatively flat floor cord, the depending flange 19 is notched as shown at 28 in Fig. 2 to receive and closely fit over the top of the cord. The conductor elements 29 and 30 of the flat cord are bared at their ends for a short length and disposed adjacent the bottom faces of the flanges of the respective contact members to which the conductor elements 29 and 30 are to be electrically connected. Clamping plates such as shown at 31 having an aperture 32 are provided with offset or bent ends 33, which bent ends are adapted to engage the bared end portions of the wires to clamp the latter tightly against the respective contact member flanges. Screws such as shown at 34 threadedly en-

gaging the nuts 20 and passing loosely through the apertures 32 in the clamping plates are provided for forcing the clamping plate towards the flanges of the respective contact members so that the bent end of each of the plates is effective to tightly clamp the respective wires into good electrical connection with the contact members. This form of connection may be readily manipulated by the most unskilled person. It is therefore a comparatively simple matter for any person to adjust the length of the floor cord 10 by cutting off such surplus length as may be originally furnished, and connecting the connector plug at the end of the shortened cord. It is obviously unnecessary to wind the ends of the conductors around the screws to insure good connection.

The flat floor cord 10 contemplated in the present case consists of electrical conductors 29 and 30 which are horizontally spaced apart and disposed in a plane common to both, the conductors being embedded in a rubber cover 36. The conductor elements 29 and 30 may be of any desirable material, but I prefer to use braided or stranded copper wire so as to secure flexibility, and also to interlock with the rubber.

The connector is preferably provided with a depending lug or stud 37 which is molded integrally with the body member 15 and which stud is adapted to engage an aperture 38 provided in the rubber covering of the conductors intermediate the two conductors.

I prefer to enclose the clamping plates 31 and other parts which are disposed in the recessed bottom of the body member and for this purpose I provide the depending annular flange 19 with a seat 39 on which an insulating material cover plate 40 may be seated. A screw 41 threadedly engaging a tapped aperture 42 in the body is provided for locking the cover plate in place, and the cover plate is preferably provided with a tongue 43 which extends into the notch 28 under the conductor cord so as to prevent the cover plate from turning and thereby possibly unscrewing the locking screw 41 from the body member.

The above described form of connector is simple in construction and may be cheaply and economically manufactured and constitutes one preferred embodiment of my invention.

I am aware that changes may be made in the form, construction and proportion of parts without departing from the spirit of the invention, the scope of which should be determined by reference to the following claims which should be construed as broadly as possible consistent with the state of the art.

I claim as my invention:

1. In a plug connector of the class described, the combination of an insulating material body member provided with an aperture extending therethrough, a contact

- member having a leg portion and a flange portion extending at an angle from the leg portion, said contact member having its leg portion disposed in said aperture and its flange portion disposed against the bottom of the body member, a clamping plate independent of said contact member, disposed flatwise adjacent said flange portion, and screw means for forcing said clamping plate towards said flange whereby the clamping plate is operative to clamp an end portion of an electrical conductor between said flange portion and the plate, thereby to electrically connect said contact member and conductor. 10
5. In a plug connector of the class described, the combination of an insulating material body member provided with an aperture extending therethrough, a contact member secured to said nut member and having a leg portion disposed in said aperture and a flange portion disposed flatwise against the bottom of said body member, a clamping plate having a portion adjacent one edge overlying said flange and offset towards the same, and a screw cooperating with said nut for forcing said clamping plate towards said flange whereby the offset edge portion of the plate is adapted to clamp an end portion of an electric conductor against the flange to establish electrical connection between the conductor and contact member. 15
15. 2. In a plug connector of the class described, the combination of an insulating material body member provided with an aperture extending therethrough, a contact member having a leg portion disposed in said aperture and a flange portion extending at an angle from said leg portion and disposed flatwise against the bottom of the body member, a clamping plate, independent of said contact member, disposed flatwise adjacent said flange portion and having a portion offset towards said flange portion, and screw means for forcing said clamping plate towards said flange whereby the offset portion of the clamping plate is operative to clamp an end portion of an electric conductor between said flange and plate, thereby to electrically connect said contact member and conductor. 20
25. 3. In a plug connector of the class described, the combination of an insulating material body member having an aperture extending therethrough, a contact member having a leg portion disposed in said aperture and a flange portion disposed flatwise against the bottom of the body member, a clamping plate having a portion adjacent one edge offset towards said flange, screw means connecting said clamping plate, at a point spaced from said offset portion, to said body member whereby the clamping plate is adapted to be forced towards said flange and said offset portion rendered effective to clamp an end portion of a conductor against the flange at a point spaced from said screw means. 30
35. 4. In a plug connector of the class described, the combination of an insulating material body member provided with an aperture extending therethrough, a contact member fixedly mounted on said body member and having a leg portion disposed in said aperture and a flange portion extending at an angle from said leg portion and disposed flatwise against the bottom of the body member, a clamping plate, independent of said contact member and overlying said flange portion and having a portion offset towards said flange portion, and screw means for forcing said clamping plate towards said flange whereby the offset portion of the
- clamping plate is operative to clamp an end of an electric conductor between said flange and plate and thereby to electrically connect said contact member and conductor. 40
45. 5. In a plug connector of the class described, the combination of an insulating material body member provided with an aperture extending therethrough, a nut embedded in said body member, a contact member secured to said nut member and having a leg portion disposed in said aperture and a flange portion disposed flatwise against the bottom of said body member, a clamping plate having a portion adjacent one edge overlying said flange and offset towards the same, and a screw cooperating with said nut for forcing said clamping plate towards said flange whereby the offset edge portion of the plate is adapted to clamp an end portion of an electric conductor against the flange to establish electrical connection between the conductor and contact member. 50
55. 6. In combination, a relatively flat duplex conductor including a pair of spaced conductors disposed in substantially the same horizontal plane, a plug connector for the end of said duplex conductor, said connector comprising an insulating material body member provided with a pair of spaced apertures extending therethrough, a pair of contact members having leg portions respectively disposed in said apertures and flange portions disposed flatwise against the bottom of the body member, a pair of clamping plates respectively overlying said flange portions and each having a portion offset towards the flange portion, screw means for forcing said clamping plates towards said flanges whereby the offset portion of the respective plates is adapted to clamp an end portion of each of the respective conductors against the flange portions so as to electrically connect the respective conductors and contact members, and means secured to said body member for enclosing said clamping plates and conductor end portions. 60
65. 7. In a plug connector of the class described, the combination of an insulating material body member provided with an aperture extending therethrough, a contact member having a leg portion disposed in said aperture and a flange portion extending at an angle from said leg portion and disposed flatwise against the bottom of the body member, a clamping plate having a portion adjacent one edge overlying said flange portion and having a portion offset towards said flange portion, and screw means for forcing said clamping plate towards said flange whereby the offset portion of the
